UNITED STATES PATENT OFFICE.

THOMAS F. MORGAN, OF PATERSON, NEW JERSEY, ASSIGNOR TO MORGAN SILK COMPANY, INC., OF PATERSON, NEW JERSEY, A CORPORATION OF NEW JERSEY.

CROSS-WEAVING LOOM.

Application filed June 11, 1923. Serial No. 624,597.

To all whom it may concern:

Be it known that I, THOMAS F. MORGAN, a citizen of the United States, residing at Paterson, in the county of Passaic and State of New Jersey, have invented certain new and useful Improvements in Cross-Weaving Looms, of which the following is a specification.

This invention relates to looms for cross-weaving of the class in which the shedding means includes a comb-like set of warp-guiding devices all projecting in the same direction at an angle to the plane of the warp and having apertures receiving the respective threads of one sheet of the warp and in which there is means to operate the shedding means which causes said set of devices to alternately project through and stand retracted from the other warp-sheet 20 and also means to cause movement laterally of the warp as between said other warp-sheet and said set of devices when the latter is in retracted relation to the former; whereby the filling may be passed through the shed 25 formed each time said set of devices assumes a projecting-through relation to said other sheet and each time the said relative lateral movement occurs the threads of one sheet are crossed with respect to those of the other. In these looms as heretofore constructed the practice has been to hold the warp for the forming of the sheds the same as is done in plain looms, and this was responsible for the binding together of the 30 threads of one sheet with those of the other back of the shedding means so that it was difficult to weave with some warp materials and practically impossible with others. The principal object of this invention is to provide a cross-weaving loom in which this 35 objection will be overcome.

In the drawings,

Fig. 1 is a front elevation of a cross-weaving loom embodying the present invention;

Fig. 2 is a front elevation and vertical section of the rear reed;

Fig. 3 shows in side and rear elevation the means for reciprocating the front and 50 rear reeds vertically;

Fig. 4 is a plan of the auxiliary reed; and Figs. 5 and 6 are diagrams.

The loom-frame *a* having the breast-beam *a'*; forward-and-back-moving batten *b* and 55 the reed *c* thereon; the means for reciprocating

the batten including the crank-shaft *d* rotated through gearing *e* from the suitably rotated drive-shaft *f* and having suitable connections (as pitmen, not shown) connecting its cranks with the batten; the shuttle *g* on the batten and the shuttle-boxes *h* and picking means *i* therefor; and the take-up means including the cloth-beam *f'* are or may be all the same as usual.

Back of the batten is the shedding means. 65 In the present instance this comprises two reeds *j* *k*, the former in advance of the latter. The reed *j* has dents *j'* and alternating with and between the dents and upstanding from the lower bar of the reed a set of flat needles *j''*, each having at its free or upper end a thread-aperture or eyelet *j''*, all the dents and needles being spaced from each other to permit the warp threads to lie between them. The reed *k* has spaced dents *k'* each 75 having at its lower end a thread-aperture or eyelet *k''*.

Journaled in the arch of the frame above the reeds *j* *k* are two conical pulleys *m* with their axes arranged to extend from front to rear and having their smaller ends forward; they have arms *m'* which are connected by a link *n* and they are thus adapted to rock together. Flexible connections *o* are attached to reed *j* and also to the pulleys at 85 their smaller diameters, extending in one direction around the same; other flexible connections *p* are attached to reed *k* and also to the pulleys at their larger diameters, extending in the other direction around them. 90 When the pulleys are oscillated the reeds are obviously reciprocated in opposite directions, the range of movement of reed *j* being less than that of reed *k*. The sheet *A* is threaded through the eyelets of the 95 warp-guiding devices formed by needles *j''* of reed *j*, while warp-sheet *B* is threaded through the eyelets of the warp-guiding devices formed by dents *k'* of reed *k*.

The reed *j* has lateral lugs *j''* which are 100 loosely penetrated by vertical rods *q* secured to the loom frame, so that the reed in moving vertically is guided substantially rectilinearly. The reed *k* is steadied in its up and down motion by springs *r* which may 105 connect it with the floor.

For causing the shedding motion the pulleys are oscillated and the reeds reciprocated from the crank-shaft to a crank-pin *s* of a wheel *t* on which is connected one end of 110

a pitman u whose other end is connected to a bell-crank lever v fulcrumed on the frame and in turn connected with the link n . The relative movement as between the reeds laterally is caused in the present case by moving laterally the reed k which for that purpose has a depending vertically slotted arm k^3 receiving the pin w' of a bell-crank lever w fulcrumed in the frame and actuated from 10 an eccentric x on the drive-shaft through a pitman y which is connected to the bell-crank lever and has an eccentric strap y' embracing the eccentric. The gearing g is such that the shafts f and d rotate in a 15 1-2 ratio; hence, it being understood that the reeds, reciprocated in opposite directions, fully open the shed (Fig. 5) and then position the two sheets of warp for effecting the cross (Fig. 6) in each revolution of 20 the crankshaft, it will be apparent that each time the two reeds assume the latter position the reed k also is made to complete a lateral movement (right or left) so that the cross will be effected and in the next movement to open or form the shed the warp-guiding devices j^2 will project through warp-sheet B laterally offset with respect to their previous corresponding movement. 25 The warp sheets are delivered from a let-off beam z and extend over rollers 2, 3, the threads of sheet A passing under a guide afforded by a bar 4 which may be a part of an auxiliary reed 5 secured by its projecting arms 6 (Fig. 4) to the loom frame 30 below the range of vertical movement of warp-sheet B.

In ordinary cross-weaving looms of this class the crossing operation produces a crossing or partial wrapping-around of the threads of one sheet with respect to those of the other not only forward of the shedding mechanism but rearward thereof. This crossing entails the intersnarling of the fibres of the two sheets which if not prevented will 40 lead to their being bound together; forward of the shedding means this binding together does not become effective to the point of being troublesome because of the motion of the reed and because of the forward convergence of the sheets, but back of the shedding means, where there is nothing to disturb its formation and where the sheets diverge forwardly, it always gives trouble in cross-weaving and when the warp threads 45 are composed of certain materials it makes it entirely impossible to carry on the weaving. In my loom this is entirely avoided because means is provided (bar 4) which pre-

vents the shedding motion being imparted to the portion of the warp back of the shedding means, i. e., which prevents a relative passing of the portions of the sheets rearward of the shedding means as a consequence otherwise of the shedding motion imparted to the warp. In the present example, the portion of one sheet back of the shedding means is kept from moving up and down and also kept clear of the corresponding portion of the other sheet; but this specific condition is not material so long as the shedding motion is prevented from being imparted to the part of the warp back of the shedding means.

The reed 5 performs the following function: On account of the angular disposition which the sheet A is compelled to take when the guiding devices j are in their elevated position, and as an incident of the advance of the warp as the fabric is formed, the twist in the threads of the sheet A becomes augmented; this augmentation in the twist being generated at and back of the apertures j^2 and extending back to guide 4, and this twisting causes the fibres of the different threads to catch together and bind the threads to each other. The reed 5, which receives a thread in every dent, keeps the threads apart and thus prevents their binding together.

Having thus fully described my invention, what I claim as new and desire to secure by Letters Patent is:—

A cross-weaving loom having means to support the warp, shedding means including a comb-like set of warp-guiding devices having free ends formed with apertures receiving the respective threads of one sheet of the warp, means to alternately move said devices through and withdraw them from the other warp-sheet, means to cause movement laterally of the warp as between said other warp-sheet and said set of devices when the latter stand withdrawn, means, with reference to which said devices are moved through and withdrawn from said other warp-sheet, for preventing the movement of the portion of the first warp-sheet rearward of the shedding means through the other warp-sheet with said devices, and a reed having its dents separating the threads of the first warp-sheet and arranged between the last-named means and said set of devices.

In testimony whereof I affix my signature.

THOS. F. MORGAN.
